United States Patent Office

Des. 183,676
Patented Oct. 14, 1958

183,676

BALL POINT PEN OR THE LIKE

Louis A. Bickley, Trumbull, and David Glantz, Bridgeport, Conn., assignors to The Waterbury Pen Co., Stratford, Conn., a corporation of Connecticut

Application March 24, 1958, Serial No. 50,154

Term of patent 14 years

(Cl. D74—17)

Fig. 1 is a side elevational view of a ball point pen showing our new design;

Fig. 2 is a rear elevational view of the cap portion; and

Fig. 3 is a top plan view thereof.

The essential features of our design reside in the parts shown in the full lines.

We claim:

The ornamental design for a ball point pen or the like, substantially as shown and described.
